APPARATUS FOR MAKING CONTINUOUS
SLIVER OF RAYON STAPLE FIBERS

Kurt Jehle, Dessau, and Karl Schmauder, Bitterfeld, Germany, assignors, by mesne assignments, to Walther H. Duisberg, New York, N. Y.

Application September 3, 1938, Serial No. 228,266
In Great Britain October 20, 1937

8 Claims. (Cl. 164—61)

The present invention relates to a device for cutting continuous bundles of artificial filaments without disarranging the substantially parallel position of the artificial fibers within the bundles.

Processes and apparatus for making slivers of rayon staple fiber from continuous artificial filaments have already been proposed; according to these proposals the bundles of continuous filaments were to be intermittently cut either at right angles or obliquely or in stepwise succession so that by joining, folding, doubling and drawing they are united to form a sliver.

The object of the present invention resides in the provision of an improved apparatus with which the cutting of continuous bundles of filaments is possible in an uninterrupted progressive cut either at right angles or obliquely through the surface of the bundle.

A further object of the invention resides in the provision in an apparatus of a character described of a device capable of removing the sections of the fiber tuft which pass through the cutting device without substantially disturbing the parallel position of the individual fibers.

Still further objects of the invention reside in certain details of construction which will become more readily apparent from the following detailed specification.

Reference is made to the accompanying drawings in which

Figure 1 is a diagrammatic cross sectional view of an apparatus according to the invention whereas

Fig. 1a is a schematic elevation showing in greater detail the operation of a clamping device in said apparatus.

Figure 2 is a plan view of the apparatus shown in cross section in Figure 1.

Fig. 2a is a diagrammatic plan view similar in part to that of Fig. 2 and intended to illustrate further the operation of the clamping device shown in detail in Fig. 1a.

Figure 3 shows another possible modification of the apparatus showing a slightly different device for advancing the bundles of continuous filaments towards the cutting machine while

Figure 4 shows a special arrangement of a device for removing the tufts in the form of a continuous sliver without substantially altering the direction and alignment of the individual fibers.

Figure 5 is a diagrammatical view of a cross section of the apparatus shown in a horizontal section in Figure 3.

Figure 6 shows a part of the device of Figure 3 in cross section as will become more clearly apparent from the detailed description of the figures following hereinafter.

In Figure 1, on a frame rotatable around the shaft 1 are mounted a number, say 26-40 or more,

of lap-rods 2, 2a, on which are spooled endless bundles of filaments 3, 3a. These bundles or bands are withdrawn over suitable guides through perforations 15 in an upper disc 4 into the space 5 between the said upper disc and the lower disc 6, both of which rotate on the shaft 1; as they are drawn between the discs the bands are continuously spread outwards over the margin of the broader lower disc. On the periphery of the upper smaller disc 4 are mounted clamping devices 5, 5a, which act similarly to tentering clips on fabric drying machines, in that they firmly press the bands of fiber onto the surface of the lower disc at certain places. Both discs rotate in the same direction and at the same speed as the frame carrying the lap-rods 2, 2a rotates on the shaft 1.

The apparatus may be so arranged that the continuous fibers are drawn over the edge of the lower disc either at one or at several places, for example by pairs of draft rollers 13 (Figure 2) which are adapted to rotate on their axes at adjustable speeds. A stationary cam rail 30 as shown in Figs. 1a and 2a fixedly mounted so as not to rotate with disks 4 and 6 may for instance determine the subsequent closing of the clamping devices 5 whereby the tufts of filaments drawn out by the draft rollers are held in a predetermined position. On the further rotation of the discs 4 and 6 the tufts of fibers are engaged and stretched by a rapidly moving draft device 8, 9, 10 which may consist of a pair of leather bands 8 and 11 or a set of fallers and a leather band or two sets of fallers. The pressure of the draft device is so adjusted that the cut fibers are drawn away, while those which are not cut slide and are held back. The filaments of the bundles are successively cut by a rotating disc knife 1, Figure 2, or by a band knife 16, Figures 3 and 4. The knives, which may be arranged at one or more positions about the periphery of the discs 4 and 6 with their accompanying draft devices, may have their cutting edge at right angles or obliquely to the axis of the bundle of continuous filaments. Oscillating knives may be used with advantage. According to the speed of rotation on the shaft 1 and of the draft device 13, the staple length 14 of the cut fibers projecting over the edge of the lower disc 6 may be varied; the cut fibers are removed without changing their substantially parallel position.

Cam rail 30, by reason of its shape as shown in Fig. 2a, acts upon the arms of clamping devices 5 as they come in contact with the cam rail in the course of their rotation with disks 4 and 6 about shaft 1. If, when viewing the apparatus from above, the disks and the clamping devices rotate in clockwise direction, the latter will, at a predetermined point, come in contact with cam rail 30 and, in sliding along said rail, be brought to the

upright and closed position shown at the right of Fig. 1a. This position is maintained for a likewise predetermined distance by an extension of the cam rail. At a point reached after completion of the cutting operation, the clamping devices 5 are opened again by the action of cam rail 30 shaped so as to act upon the upper portion of the clamps so that they will assume the open and inclined position shown at the left of Fig. 1a.

The coherent sliver of fibers withdrawn by the device 8-12 may be delivered to a cross winder or into a can. However, the cutting device according to this invention may also be combined with a machine for further operations.

When the drawing, clamping, cutting and removing devices are arranged at several positions around the discs, for example four times, the slivers formed individually at these places may be combined at one place, doubled, drawn, and united to form a single sliver.

Another modification is shown in Figs. 3 and 5. In this instance disks 4' and 6 are equal in diameter. The clamping devices used in the modification, illustrated in Figs. 1, 1a, 2 and 2a, momentarily to clamp the filaments, are replaced by open linked chains 18 and 18a. Reference to Fig. 5, and especially to Fig. 6, will explain their action. These chains are pressed together by the action of support 27 and members 26 due to the action of compression springs 28, shown to best advantage in Fig. 6. It is self-evident from Figs. 5 and 6 that the two chains 18 and 18a will grip the ends of the continuous bundles of fibers issuing from disks 4' and 6 as long as said fibers are between the portions of the chains which are pressed together. For the purpose of making this length of gripping path adjustable, one of the pressing members 26 or 27, preferably 26, as shown in Fig. 6, can be made adjustable in length. Due to the tangential arrangement of chains 18 and 18a with respect to disks 4' and 6, the chains grasp the fibers and withdraw them from said disks. The length of the fibers withdrawn depends, of course, upon the extent of the gripping action by chains 18 and 18a. Thus, for example, the greater the distance the two chains are pressed together, the longer will be the tufts of fibers withdrawn. Instead of using a disk knife, as in the modification illustrated in Figs. 1 to 2a, it is preferable to employ a band knife.

16. The moving band knife 16, shown in Fig. 3 for example, travels around the entire device. If it is desired not to encircle the disk completely with a moving band knife, it may be doubled back upon itself, as shown in Fig. 4. It is preferable to give a slight angle to the moving band knife, as shown in Fig. 6, so as to prevent premature cutting of the fiber tufts. It is, of course, also possible to arrange the moving band knife vertically with respect to the rotating disks so that it will have precisely the same action as a rotating disk knife.

Figs. 3 and 5, on the one hand, and Fig. 4, on the other, show two further modifications by means of which the cut fibers can be withdrawn from the device. The arrangement shown in Figs. 3 and 5 shows that slivers b are gripped between belts 19 and 21 mounted on rollers 20. For the purpose of illustration, belt 19 and the rollers over which it is transported are not shown in Fig. 3. The slivers then pass through a set of

rollers 22 and between belts 23 and 24 whereupon a set of rollers 25 lead them either to a can or to a cross winder. The modification illustrated in Fig. 4, used for taking care of the slivers after they are cut, consists in a drum 29 the axis of which is parallel to the axis of the disks. The drum is filleted like the main drum of a card. The sliver formed thereon may be removed by means of withdrawing rollers or the like.

We claim:

1. A device of the character described comprising in combination, a number of lap-rods rotatably mounted on a frame, bundles of continuous filaments on said lap-rods, a rotatable axle carrying said frame, two discs mounted on said axle, the upper disc comprising a series of perforations adapted to permit said bundles of continuous filaments to be withdrawn there-through, means for continuously withdrawing a tuft of fibers from said bundles of filaments on said lower disc, means for cutting said tuft of fibers, and means for removing the cut tufts of fibers in the form of a continuous sliver without disturbing the parallel arrangement of the individual fibers.

2. A device as defined in claim 1 wherein said means for cutting consists of rotating disc cutters.

3. A device as defined in claim 1 wherein said means for cutting consists of running band cutters.

4. A device as defined in claim 1 wherein said means for continuously withdrawing a tuft of fibers from the bundles on said disc comprises a pair of drawing rollers arranged close to the periphery of said lower disc.

5. A device as defined in claim 1 wherein said means for continuously withdrawing a tuft of fibers from the bundles on said disc comprises a pair of open linked chains.

6. A device as defined in claim 1 wherein said means for continuously removing the sliver comprises leather belts, the tension of said leather belts being so adjusted as to transport away the cut fibers while letting the uncut fibers slide through.

7. A device as defined in claim 1 wherein more than one withdrawing means and more than one cutting means are arranged tangentially around said discs.

8. A device of the character described comprising in combination, a number of lap-rods rotatably mounted on a frame, bundles of continuous filaments on said lap-rods, a rotatable axle carrying said frame, two discs mounted on said axle, the upper disc comprising a series of perforations adapted to permit said bundles of continuous filaments to be withdrawn there-through, means for continuously withdrawing a tuft of fibers from said bundles of filaments on said lower disc, clamping means capable of holding said tuft of fibers in position said clamping means being in operative connection with said withdrawing means, means for cutting said tuft of fibers, and means for removing the cut tufts of fibers in the form of a continuous sliver without disturbing the parallel arrangement of the individual fibers.
